CONTAINER-DRAWER STOP AND
ALIGNING MEANS

Philip Zalkind, New York, N. Y.

Original application June 2, 1938, Serial No. 211,385, now Patent No. 2,337,079, dated December 21, 1943. Divided and this application January 1, 1944, Serial No. 516,681

3 Claims. (Cl. 45—7)

1

This invention is a division of my application Serial No. 211,385, filed June 2, 1938, which has become Patent No. 2,337,079, dated Dec. 21, 1943, and relates to collapsible containers wherein a collapsible drawer is intended to be slideable into and out of the open front of a casing, and in connection with which novel drawer stop and aligning means are provided.

Such casings and drawers may be economically constructed of fibrous sheet material, the casing being reinforced and strengthened, particularly at the open front, by means such as that provided in my Patent No. 2,118,011, issued May 17, 1938, and may be strengthened in the rear, if necessary, by the inset back construction set forth in my Patent No. 2,159,070, issued May 23, 1939, the drawer being formed substantially as described in my Patent No. 1,946,516.

When the casing and drawer combination is used as a transfer file for storage of records and papers or for any other purpose involving the loading of the drawer with relatively heavy material, the movement of the drawer may be impeded by the friction developed between the bottom of the drawer and the floor of the casing. Accordingly, in my Patent Nos. 2,233,906 and 2,200,319, as well as in other patents herein set forth, I have provided for various types of friction reducing means and mechanisms between the casing floor and the drawer bottom. Likewise, in my Patent No. 2,319,283, issued May 18, 1943, I have provided for additional and improved friction reducing means.

Where, by the use of efficient anti-friction means, the movement of the drawer is facilitated to the extent that only a minimum of effort is required to operate it, it becomes necessary to provide means such as drawer-stop to prevent undesired or intended removal of the drawer from the outer casing. Such drawer-stop should, where possible, reinforce both the drawer and the casing, facilitate the operation of the drawer, and even serve to suspend the drawer when it is so far withdrawn that its center of gravity is outside the casing; and it should not interfere with the collapsibility of casing and drawer where that is a factor. Such drawer stop may be provided in connection with a reinforcing member as shown in my Patent No. 2,210,019, or may be independent thereof.

Objects of this invention, therefore, are to provide in a casing and drawer combination a drawer stop which may, if desired, cooperate with any anti-friction means which may be used (and particularly the anti-friction means set forth in my

2

Patent No. 2,319,283, issued May 18, 1943, in order to align the drawer with said anti-friction means; a drawer stop which will permit withdrawal of the drawer and yet serve as a stop for the drawer when withdrawal thereof is not desired; that will not interfere with collapsibility of drawer and casing; and that may even serve to suspend the drawer when it is partially removed from the casing.

10 Other objects and uses of my invention will, in part, be apparent and in part indicated in the following description and drawing in which:

Figure 1 is a view in perspective of a casing and drawer showing a form of drawer stop which 15 features my present invention.

Figures 2 and 3 are details of the drawer stop of Figure 1.

The drawer of Figure 1 may have a roller 401 mounted on the back wall in such manner that 20 it will just clear the inner surface of the top wall of the casing when the drawer is inserted therein.

Many methods may be used for mounting such 25 roller on the drawer. I prefer, however, to use a drawer blank the rear construction of which will be like that of the blank, Figure 26 in my Patent No. 2,319,283, issued May 18, 1943. The back wall 400 in such blank of Figure 26 of that patent consists of a panel 402, separated by a bend line 403 from the bottom wall 131; the panel

30 402 is in turn separated by a double score line 404 from the inner panel 405. The panels 402 and 405 are cut out at 406. Panel 405 may then be turned on the double score line 404 to lie in face to face relation against the panel 402. An

35 additional panel 407 may be adhesively or otherwise mounted so that it will lie between the panels 405 and 402 when they are folded together. The edges 408, 409 of the panel 407 may then serve as a support for a wire 410 (cf.

40 Fig. 43), said wire carrying the roller 401 which projects above the slot 406. The back wall assembly may be secured together in the manufacturing process, such back wall assembly for 45 mounting the roller not interfering with the collapsibility or flat shipment of the drawer. The roller wire may be secured so that the roller will at all times be held in operative position.

Such roller 401 (Figure 1) will furnish additional 50 rolling support or suspension for the drawer by bearing against the top wall of the casing when the drawer is so far removed from the casing that its center of gravity is beyond the casing mouth, the drawer then tending to sag down at its forward end. And such roller may 55 also cooperate with any stopping means provided

in the top wall of the casing and thereby act as a drawer stop. Such roller may also serve as a handle for the rear wall of the drawer to facilitate lifting the drawer when it is entirely removed from the casing.

In Figure 1, I have illustrated one type of stopping mechanism for the casing adapted to cooperate with such roller 401 or any other raised portion or extension of the rear wall of the drawer or even the rear wall of the drawer itself to create a drawer stop. A U-shaped wire 411 is mounted in a plate 412 mounted in the top wall 413 of the casing 40. Such U-shaped wire remains normally in the lowered or hanging position as illustrated in the figure. It is so arranged that it cannot swing forward toward the open mouth of the casing, and thus, when engaged by the roller, will not permit unintended movement of the drawer out of the casing. But when it is desired to permit the roller 401 to pass beyond the wire 411 so that the drawer may be pulled out, the wire 411 may be swung backward toward the rear of the casing and thus raised.

As seen in the detail view of Figure 2, the plate 412 may comprise a flat member 414 having two risers 415, 416, the riser 416 having perforations 417, 418 associated with recesses 419, 420 within which the ends 421, 422 of the U wire 411 may be inserted so that they will not project beyond the plane of the riser 416 or the plane of the flat member 414. As will be clear from the figure, the U shaped wire may be freely swung away from the riser 416, but cannot swing any further toward such riser and is effectively stopped thereby. The plate 412 may be inserted in a gap 425 (Figure 1) in the roof 413 of the casing 40 so that the flanges 423 and 424 extend beyond the edges of such gap to prevent the lifting of such plate away from the casing. The U wire 411 will then hang down into the interior of the casing to serve as a drawer stop in cooperation with the roller 401. A batten 426 (Figures 2 and 3) may then be inserted beneath the flat member 414 so that the ends of the batten rest against the outer surface of the top wall of the casing and prevent the plate 412 from falling into the casing and will lock the drawer stop in place. The stud 427 on the batten 426 cooperates with the perforation 428 of the flat member 414 to prevent accidental removal of the batten where casings are to be placed one on top of the other, the batten 426 may be flat so that the flat member 414 will be very nearly flush with the top of the casing. A channel member 429 may be mounted over the forward edge of the gap 425 to reinforce such forward edge against any undue pressure or strain when the roller 401 is pulled against the drawer stop 411.

The construction herein shown will operate in a rigid or collapsible container without interfering with the collapse of the container, casing or drawer. The rotation of the wire toward the rear will raise the wire to lie flat against its wall to permit collapse.

Further, the fact that the wire 411 is rotatable in one direction to lie flush with the wall but will resist rotation in the opposite direction will suggest many other uses for such wire in collapsible structures. Thus, such constructions may be used as of hanging or suspending means in the ceiling of collapsible cabinets or even in the side walls thereof.

From the foregoing description it will be apparent that my invention resides in certain prin-

ciples of construction which may be embodied in other physical forms without departure therefrom. I do not, therefore, desire to be strictly limited to the disclosure as given for purposes of illustration but rather to the scope of the appended claims.

Having described my invention, I claim:

1. In a collapsible cabinet comprising a collapsible casing section of substantially fibrous material having a top wall and an open front and a collapsible drawer section of substantially fibrous material having side walls and an open top and a rear wall; means on said top wall of said casing section and means on said rear wall of said drawer section cooperating with each other to prevent unintended removal of the drawer section from said casing section; said means on said rear wall of said drawer section comprising a roller adapted to ride against the top wall of the casing section; said means on the top wall of the casing section comprising an abutment engaging said roller and preventing unintended removal of the drawer; said abutment comprising a support in the top of the casing section, a pendant rotatable wire having a portion in the path of movement of said roller, means on the support cooperating with the wire for limiting rotation of the wire toward the front of the casing section, said wire being rotatable toward the rear of said casing section to be raised out of position to engage with said roller; said support being carried by the top wall of the casing and comprising a channel shaped member having a main channel section defined by a pair of parallel legs and a bridging member connecting them; flanges secured to and extending from the said legs; recesses at the connection between one of said legs and said bridging element; extensions on said rotatable wire engaged in said recesses for supporting said wire.

2. In a collapsible cabinet comprising a collapsible casing section of substantially fibrous material having a top wall and an open front and a collapsible drawer section of substantially fibrous material having side walls and an open top and a rear wall; means on said top wall of said casing section and means on said rear wall of said drawer section cooperating with each other to prevent unintended removal of the drawer section from said casing section; said means on said rear wall of said drawer section comprising a roller adapted to ride against the top wall of the casing section; said means on the top wall of the casing section comprising an abutment engaging said roller and preventing unintended removal of the drawer; said abutment comprising a pendant rotatable wire, a support for said wire in the top of the casing section said wire having a bent portion in the path of movement of said roller and other portions rotatably secured to said support, the motion of said wire toward the front of said casing section being limited, said wire being rotatable toward the rear of said casing section to be raised out of position to engage with said roller; a support for said wire, said support being carried by the top wall of the casing and comprising a channel shaped member having a main channel section defined by a pair of parallel legs and a bridging member connecting them; flanges secured to and extending from the said legs; recesses at the connection between one of said legs and said bridging element; extensions on said rotatable wire engaged in said recesses for supporting said wire; said last mentioned leg also providing a stop for said wire lim-

iting the rotation of the wire toward the front of the casing section.

3. In a collapsible cabinet comprising a collapsible casing section of substantially fibrous material having a top wall and an open front and a collapsible drawer section of substantially fibrous material having side walls and an open top and a rear wall; means on said top wall of said casing section and means on said rear wall of said drawer section cooperating with each other to prevent unintended removal of the drawer section from said casing section; said means on said rear wall of said drawer section comprising a roller adapted to ride against the

top wall of the casing section; said means on the top wall of the casing section comprising an abutment engaging said roller and preventing unintended removal of the drawer; said abutment comprising a pendant rotatable wire, a support for said wire in the top of the casing section, said wire having a bent portion in the path of movement of said roller and other portions rotatably secured to said support, and means on the support cooperating with the wire for limiting rotation of the wire toward the front of the casing section.

PHILIP ZALKIND.
